UNITED STATES PATENT OFFICE.

JAMES R. FLEMING, OF SCRANTON, PENNSYLVANIA.

JOURNAL-BEARING.

1,075,204.

Specification of Letters Patent. Patented Oct. 7, 1913.

Application filed November 9, 1911. Serial No. 659,268.

To all whom it may concern:

Be it known that I, JAMES R. FLEMING, a citizen of the United States, and a resident of Scranton, in the county of Lackawanna and State of Pennsylvania, have invented a new and Improved Journal-Bearing, of which the following is a full, clear, and exact description.

Among the principal objects for which the present invention is designed are: To provide self-aligned bearing boxes and supports therefor, constructed and arranged to be readily removed from the car and axle for repair or replacement; to provide a simple, economical and efficient bearing box for mining cars and similar vehicles; and to provide a hanger and bearing box removably supported thereby, constructed and arranged with reference to the avoidance of a requirement for machine-work when assembling said bearing and hanger with the axle of a wheel.

Reference is to be had to the accompanying drawings forming a part of this specification, in which similar characters of reference indicate corresponding parts in all the views, and in which—

Figure 1 is a side view of a bearing constructed and arranged in accordance with the present invention, the axle of a vehicle seen in conjunction therewith being shown in section; Fig. 2 is a bottom plan view, partly in section, of the bearing constructed and arranged in accordance with the present invention, the section being taken on the line 2—2 in Fig. 1; and Fig. 3 is a vertical section taken on the line 3—3 in Fig. 1.

As seen in the accompanying drawings, the axle A is mounted in a bearing box 8. The box 8 is shown as provided with a friction-reducing bearing formed of rollers B. Any suitable form of friction-reduction bearing may be employed as a substitute for that shown, the character of bearing employed being optional.

As seen in the accompanying drawings, the box 8 is formed independent of the hanger in the bracket sides at 9, with which it is provided. In practice, the axle A may be independently equipped with the bearing boxes 8 and the bearing rollers B contained therein. To hold the bearing rollers B in position within the box 8 I have formed at one end of the said box the closure end 10, and at the other end a slot to hold the ring

cover 11. The ring cover 11 is perforated, as is the closure end 10, to pass the axle A. The closure end 10 receives the thrust of the hub of the wheel C. As seen in the drawings, the box 8 is crowned lengthwise. The extent of the curvature of the crown is cylindrical and tapers toward its ends, and as shown in the drawings, is for purpose of illustration, exaggerated. The surface of the box 8 bears upon the base-plate 13 from which the brackets 9, 9 are extended. In the preferred form of base-plate 13, the same is provided with a boss 14, spherical in shape to rock on the said box 8 in a manner similar to that of a universal joint.

The brackets 9, 9, as indicated, serve to support the box 8 when the body of the car is lifted to lift the carrying wheels thereof. For this purpose, the lower end of each of the brackets is provided with a groove 15. The grooves 15 are shaped to receive elongated ear tabs 16 extended from the side of the box 8 at the longitudinal center and midway between the ends thereof. The grooves 15 are open at one end, and at the other end are closed. The side walls of the grooves 15 are straight, while the top and bottom sides and the outer edges of the tabs 16 are rounded or crowned, as seen best in Figs. 1 and 2 of the drawings.

By employing a cylindrical bearing box and providing it with ear tabs or lugs arranged as described, the box can be inverted or reversed when one side becomes worn, thereby prolonging the life of the said box, and by curving or rounding the edges of the ear tabs or lugs, a rolling joint is formed in the grooves of the brackets, so that breakage is reduced to a minimum and the noise incident to the bearing separating from the base plate is prevented.

By employing hangers constructed and arranged as shown, the need of the usual bracing collar on the axle is dispensed with. By this construction the lateral axle thrust is received on the tabs 16, and closed end of the hanger brackets 9, 9. The end thrust of the hangers on the boxes 8 is imparted initially to the tabs 16. By rounding the surfaces of the said tabs any disadjustment of the axles A is compensated for to avoid imposing on the boxes 8 a cramping or grinding strain. It will thus be seen by reference to the accompanying drawings and to the foregoing description, that each part

of the box 8 and bearing members thereon is rounded where the same is liable to contact with the hanger or any part thereof.

Having thus described my invention, I claim as new and desire to secure by Letters Patent:—

A journal bearing, comprising a base plate provided with two spaced depending brackets, each having on its inner face at the lower end a groove leading out through one end of the bracket and terminating short of the other end of said bracket, said base plate being provided between the brackets with a spherical boss forming a bearing, and a cylindrical bearing box tapering toward its ends and provided on opposite sides at its

longitudinal center and midway between the ends with elongated lugs having curved outer edges and fitting in the grooves of the brackets, whereby the bearing may be inverted and will be held so as to be free to rock without noise and danger of breakage incident to the separation of the bearing and base plate.

In testimony whereof I have signed my name to this specification in the presence of two subscribing witnesses.

JAMES R. FLEMING.
